No. 802,675.

PATENTED OCT. 24, 190

C. E. AVERY.
ELECTRIC BELL.
APPLICATION FILED MAR. 16, 1904.

UNITED STATES PATENT OFFICE.

CHARLES E. AVERY, OF JERSEY CITY, NEW JERSEY, ASSIGNOR TO MANHATTAN ELECTRICAL SUPPLY COMPANY, A CORPORATION OF NEW JERSEY.

ELECTRIC BELL.

No. 802,675.

Specification of Letters Patent.

Patented Oct. 24, 1905.

Application filed March 16, 1904. Serial No. 198,415.

To all whom it may concern:

Be it known that I, CHARLES E. AVERY, a citizen of the United States, and a resident of the city of Jersey City, Hudson county, New Jersey, have invented certain new and useful Improvements in Electric Bells, of which the following is a full, clear, and exact description, reference being had to the accompanying drawings, forming a part of this specification.

My invention relates to electric bells of the suspended type, and one object thereof is the provision of means by which the proper electric circuits may be established by simply hanging the bell on its support, from which it may be removed without the necessity of unfastening the circuit-wires, which are all concealed and do not interfere with the operation of the bell.

My invention also comprises certain other novel features of construction, which are hereinafter described and claimed.

In the drawings, Figure 1 is a sectional elevation showing my improvements. Fig. 2 is a detail, partly in section, on an enlarged scale, showing the arrangement of the circuit-terminals. Fig. 3 is a detail, on a similar scale, showing the manner of connecting the circuit-wires. Fig. 4 is a sectional elevation, also on an enlarged scale, showing the contacts and a portion of the bell mechanism; and Figs. 5 and 6 show details of the armature-supporting devices.

Similar reference characters are employed to designate like parts in all the views.

The drawings show a practical embodiment of my invention in a preferred form; but it will be understood that in selecting this particular embodiment of my invention for illustrative and descriptive purposes I do not intend to limit the same to the details of construction and arrangement further than as hereinafter expressly provided.

The bell 1 is operated by a clapper 2, which is connected with the vibrating armature 3, pivotally suspended from the crown of the bell, as will be more fully described hereinafter. A magnet 5, provided with the polar extension 6, is also suspended within the bell by means of a post 7, which extends through an aperture in the crown of the bell. A hanger 9 is fitted to the projecting end of the post 7, and the nut 10 clamps the post 7 and the hanger 9 securely to the crown of the bell.

The post 7, which is preferably a continuation of the magnet-core, is provided with a horizontal groove 11. The upper or horizontal member of the armature 3 is slotted to encircle the post 7, and one edge of the slot is shaped to project into the groove 11 to form a firm pivotal bearing for the armature, and, what I also consider important, an efficient magnetic circuit is formed by reason of the extended contact thus provided between the armature and the extension or continuation of the magnet-core. The sides of the armature are provided with vertical slots 12, into which loosely enter the lugs 13 on the collar 14, carried by the post 7. These lugs by preventing lateral movement of the armature hold it in the groove 11. By this construction also these parts of the bell-operating mechanism may be inexpensively constructed and readily assembled.

The post 7 is counterbored to receive an insulating-plug 15, which supports a contact-stud 16. The stud 16 is connected with one terminal of the magnet-coils by the wire 17, extending through the post 7. The stud 16 and wire 17 are insulated from the post 7, and consequently from the bell and the magnet-supporting devices.

The opposite terminal of the magnet-coils is connected by the wire 18 to the armature-contact arm 19, which may be stamped from a single piece of metal and is secured in position by having its edges bent over the insulated head of the magnet 20. A spring-tongue 21 on the armature is normally held against the armature-contact by the weight of the hammer 2, thus normally forming a metallic connection through the armature 3 and post 7 to the hanger 9.

The arm 25 is secured, as by screws 26, to a plate 27, which may be fastened to any suitable support. The arm 25 is hollow and is provided with an aperture 28, behind which in an aperture in the plate is secured an insulating-block 29 by the binding-screw 30, Fig. 3, which passes through the block 29 into the end of the arm 25 and to which one of the generator-circuit wires is connected. The arm 25 and its hook 32 thus form one terminal of the circuit. The other wire of the generator-circuit is connected with the binding-screw 33, carried by the insulating-block 29. Within the hollow arm 25 is the insulated conducting-wire 34, one end of which

is connected with the binding-screw 33, and the other end, passing through a hole in the arm 25, is clamped between the metallic spring-tongue 36 and the insulating-strip 37 by the screw 38. The tongue 36 is completely insulated from the arm 25 and hook 32 by the strip 37, which is preferably formed of fiber or other similar material pressed into shape. The metallic tongue 36 thus forms 15 the other terminal of the generator-circuit and is so shaped and adjusted that when the hanger 9 of the bell is placed on the hook 32 the tongue 36 will be held against the top of the stud 14 with sufficient pressure to form a 20 perfect electrical contact.

With the bell hung in position as shown in Fig. 1, if the circuit be closed by means of any suitable switch the magnet 5 will be energized to vibrate the armature 3 and clapper 25 2 and continuously ring the bell in a manner well understood by those skilled in the art, it being, of course, understood that my invention is not intended to be limited to a vibrating or continuous-ringing bell, it being 30 equally well adapted for other well-known forms of bell-actuating mechanism.

The bell may be suspended instantly in operative position just as assembled at the factory without requiring the connection of any 35 wires and may be instantly removed by simply lifting it from the hook. Moreover, the bell will always hang free and true, which is essential to its satisfactory operation, and the appearance of the bell is also much enhanced 40 by the concealment of the circuit-wires.

Having thus shown and described my invention, what I claim as new, and desire to secure by Letters Patent, is—

1. The combination of a hollow arm pro-

vided with a bell-support adapted to be connected with one wire of the circuit, a conducting-spring carried by said arm, a connection for said spring extending through the arm and adapted to be connected with the other wire 45 of the circuit, insulating means between the arm and the conducting-spring, and contacts carried by the bell, forming terminals for the magnet-circuit and arranged to contact with the bell-support and the conducting-spring when the bell is hung in position. 50

2. The combination of a hollow arm provided with a bell-supporting hook adapted to be connected with one wire of the generator-circuit, a conducting-spring carried by said arm below the hook and insulated therefrom, 55 a connection for said spring extending through the arm and adapted to be connected with the other wire of the generator-circuit, a hanger secured to the bell and forming one terminal of the magnet-circuit, and a contact carried 60 by the bell forming the other terminal of the magnet-circuit, said hanger being arranged to engage the hook to support the bell and said contact being arranged to engage said spring when the bell is so supported. 65

3. In an electric bell, the combination of a post which suspends the bell-magnet from the crown of the bell, an armature provided with a slot through which the post extends, a transverse groove in the post arranged to receive 70 one edge of the armature-slot to form a pivoted bearing for the armature, and co-operating lugs and slots on the post and armature to hold the armature in its bearing.

CHARLES E. AVERY.
